UNITED STATES PATENT OFFICE

WILLIAM BOUDINOT CONNER, OF NEW YORK, N. Y.

EXTENSIBLE SHOE FORM

Application filed May 19, 1928. Serial No. 279,031.

This invention relates to an extensible shoe form adapted to be placed in a shoe when the shoe is not in use or when displayed as merchandise, in order to keep the shoe in the proper stretched condition to maintain its shape and prevent wrinkling of the leather, and also adapted to be used as an extensible form or last during manufacture of the shoe.

General objects of the invention include the provision of a shoe form for the above-mentioned purposes which can be readily inserted into and withdrawn from the shoe and which will be extensible and retractible in opposite directions of simultaneous movement of its heel and toe parts in the longitudinal line of the form to give a double elongation and retraction for rapidity and nicety of its extension adjustment to the situation of use and rapidity of retraction of the parts for quick removal of the form from the shoe.

Another general object of my invention is to provide a shoe form of simple construction which will contain none of the ordinary springs, catches, clips, pins etc. which heretofore have been characteristic of shoe forms in general and which, because of their destructibility and liability to get out of order, have after a certain period of use caused the form to operate unsatisfactorily. In other words, my invention contemplates the provision of a shoe form of such simplicity and durability that it can be used practically indefinitely without depreciation of its usefulness. While these general objects are attained by the structural features of my invention hereinafter referred to, they also preferably include the making of the shoe form throughout of light metal for strength and durability while still maintaining the form light enough for its intended purposes.

I am aware that the prior art presents extensible shoe forms having provision for their more rapid extension and retraction by opposite directions of simultaneous movement of the heel and toe parts in the longitudinal line of the form. But, so far as I am aware, in these prior art forms, either the mechanism for the extension and retraction of the form introduces a weak structural connection between the toe and heel parts of

the form, poorly adapted to withstand the strains imposed in use upon the extended form, or greater strength in that connection has been attained only by complications in the structure of the adjusting mechanism and substantial modifications in or additions to the usual simple heel and toe parts to mount or cooperate with that mechanism. Another disadvantage in the prior art forms has been the necessity of locking devices of various descriptions to hold the form to its extended position against the strains in use tending to retract it. Still another disadvantage in these prior art forms, especially those extensible in a double elongation by opposite directions of simultaneous movement of the heel and toe parts, is that their extensibility has been limited by the extent of opposite simultaneous movement of the heel and toe parts allowed by the mechanism providing for that movement, that limitation preventing the use of the same form or the same size of form for widely varying sizes of shoes.

Accordingly, more particular objects of my invention include the provision of a shoe form having improved mechanism for the double elongation hereinbefore referred to of relatively simple construction, requiring no substantial modification of or additions to the usual simple form of heel and toe parts to mount or cooperate with that mechanism, and which mechanism will provide, without a locking device, and in any position of extension of the heel and toe parts of the form, a strong, rigid connection between them, especially in the median longitudinal line of the form where the greatest strains are exerted tending to retract or collapse the form. Another particular object of my invention is to provide means enabling such an extension adjustment of the toe part of the form, separate from and additional to that of the double elongation referred to, as to fit the form to larger sized shoes than has heretofore been possible in a form adapted to the smaller or normal sizes.

The foregoing and other objects and the principles of the invention will more fully appear from the detailed description of a preferred embodiment of the invention herein-

after presented and illustrated in the accompanying drawings forming a part of this specification. It is to be understood, however, that the embodiment referred to is simply one example illustrative of the principles of the invention and is not to be taken as limiting the invention to that precise form, the invention including other embodiments and modifications of the embodiment shown, 10 all within the scope of the appended claims.

In the drawings:

Fig. 1 presents a top plan view of the extensible shoe form constituting, as stated above, a preferred embodiment of the invention;

Fig. 2 presents a vertical longitudinal sectional view along the line 2—2 of Fig. 1, that is, along the longitudinal median line of the form, with certain parts, such as screw shafts 13 and 14, shown in side elevation, and with the form somewhat extended beyond the condition of the form as shown in Fig. 1;

Fig. 3 presents a bottom plan view of the form in its condition as shown in Fig. 1; and

Fig. 4 presents a side elevational view of the form in its condition as shown in Figs. 1 and 3, the rear curved surface of the heel part of the form being shown in Fig. 4 somewhat broken away.

As hereinbefore stated, the structural principles of my invention are such as to enable the usual simple character of front or toe and heel parts to be used without substantial modifications thereof or additions thereto for mounting or cooperating with the mechanism to extend and retract the form. In the present example, the front or toe part and the heel part of the simple character referred to are shown at 10 and 11, respectively. They are preferably of shell-like or hollow form and preferably also of light metal, the larger part 10 which functions as the main or front foot part being also preferably perforated as indicated by the apertures 12 for further lightness of structure, such character of construction and material affording exceptional lightness and strength.

As also hereinbefore stated, when an extensible shoe form is in its extended condition in a shoe for the purpose of stretching the shoe in a manner to keep the shoe in proper shape and prevent wrinkling of the leather, considerable stresses are exerted, especially in the median longitudinal line of the form, tending to retract or collapse together the extended or spaced parts of the form. These stresses are especially severe when the shoe is drying on the form from a wet or damp condition when the form was inserted. In the novel shoe form of my invention, the mechanism for extending the form is of such structural principles as to present in all positions of extensions adjustment a rigid structural connection or abut-

ment between the front and rear parts of the form along the median longitudinal line of the form of ample strength to resist the considerable stresses exerted in this line tending to retract the parts toward each other.

In the illustrative example of the invention disclosed in the drawings, the mechanism providing both for the double extension and retraction of the form and for the rigid connection or abutment between the front and rear parts of the form, includes as an important feature oppositely aligned screw shafts 13 and 14, lying in the longitudinal median line of the form, parallel to the substantially flat sole portion 16 of the main foot or front portion of the form, and in threaded relation with the front foot and rear or heel parts of the form, respectively.

This threaded relation of the two screw shafts with the two separate parts of the form can readily be provided for in the usual simple constructions of these parts without substantial modifications of or substantial additions to those parts. Where the front foot part of the form is of solid construction that part can be provided with the required centrally extending threaded bore to receive the threaded shaft, or where the front foot part of the form is of the type of hollow construction as in the illustrative example, an end wall, 17, preferably somewhat thickened, is bored and threaded to receive the front screw shaft as shown in Fig. 2.

A convenient construction establishing threaded relation of the rear screw shaft with the rear or heel part of the form, adopted in the illustrative embodiment of the invention, is the provision of an interiorly threaded sleeve 18 to receive the screw shaft 14, with the sleeve rigidly attached to the rear portion of the curved wall of the heel part 11, as by a rivet-like projection 19 extending from the solid end wall of the sleeve 18 through an aperture provided therefor in the rear portion of the heel part 11 and headed over the outer surface of the heel part as a rivet as indicated at 20.

This alignment and spacing of the screw shafts apart enables the operating mechanism for rotating the screw shafts to be mounted between the opposed ends of the shafts and hence also between and independent of the respective foot and heel parts of the form. This arrangement constitutes another specific but advantageous feature of my novel shoe form since it obviates the complications of the structure involved in modifying or adding structures to the front or heel part of the form to mount or cooperates with the referred-to operating mechanism.

In the present illustrative embodiment of the invention, the mechanism for rotating the screw shafts comprises oppositely aligned bevel gears 21 and 22 fixedly mounted on the smooth cylindrical end portions of the screw

shafts 13 and 14, respectively, as by pins 23 extending through the gear hubs and the referred-to end portions of the screw shafts, the gear hubs and the end portions of the screw shafts, of course, being properly apertured to receive and hold these pins. The opposed extremities of the unthreaded end portions of the screw shafts 13 and 14 are preferably somewhat reduced in diameter, as indicated at 24 and 25, respectively, to project through the gears 21 and 22 into side bores in a central journal or bearing block 26, for journal engagement therewith.

This bearing block 26 is also bored from its top face to provide a journal bearing and support to a vertically disposed shaft 27, provided with a handle 28 for manual operation in rotating the bevel gear 29 fixedly mounted on the shaft 27 as by a pin 30, the bevel gear 29 by its toothed engagement with the toothed bevel gears 21 and 22, rotating the latter gears.

When the shoe form is inserted in a shoe and the mechanism operated to extend the form by simultaneous opposite directions of movement of the foot and heel parts of the form, the engagement of the substantially flat sole portion of the foot part of the form with the insole of the shoe and of the curved upper portion of the foot part of the form with the inner surface of the shoe upper prevents turning movement of the foot part of the form on its screw shaft, but there is a tendency in all shoe forms of this general character for the smaller and more sharply curved heel part to rotate on its screw shaft in its position inside the heel portion of the shoe. To prevent this turning movement of the heel part of the form, I have adopted, in the preferred and illustrative embodiment of the invention, a bracket 31, of U-shape in vertical cross section and side elevation as shown in Figs. 2 and 4, for the support and mounting of an arm or finger 32 extending over and in parallelism with the rear screw shaft 14, the arm having a slot 33 to receive a stud 34 rigidly mounted in the upper wall portion of the sleeve 18 and projecting upwardly through the slot. By this arrangement, as the rear screw shaft 14 is rotated in opposite directions, the sleeve 18 and consequently the heel part 11 of the form which is rigidly attached to the sleeve 18, is constrained to a rectilinear travel along the screw shaft, the limit of which in opposite directions is determined by the engagement of the stud 34 with the opposite ends of the slot 33 in the arm 32.

In addition to its function as a supporting mounting for the slotted arm 32, the U-shaped bracket 31 provides a housing for the gear mechanism operating to rotate the screw shafts, and, if desired, that housing may be improved in appearance by providing it with closed sides and bottom. The

U-shaped bracket form of housing now shown is, of course, properly apertured in its depending side portions for the free turning of the screw shafts therein. While this presents a bracket having some slight tendency, shared also by the upper bevel gear 29, to turn about the screw shafts as a center when the shoe form is manipulated while out of its position of use in a shoe, it has been found that with a fairly steep pitch or inclination of the threads on the screw shafts, as shown in the drawings, and with a bevel-gear arrangement of the type here shown for rotating those shafts, there is no tendency whatever of the bevel gears, bracket or screw shafts to turn from any position of their extension adjustment when actually in use in the shoe. In fact, the entire operating mechanism, including the screw shafts with their threaded relation to the foot and heel parts of the form and the gear mechanism, function under the stresses imposed by the shoe on the extended form to provide a rigid connection between those parts of the form, with that connection extending in the line of the greatest stresses exerted on the form, the median longitudinal line through the form, and acting in the nature of an abutment between the two parts of the form to resist any retraction of those parts toward each other. In this manner, the operating mechanism referred to automatically locks the form in its position of extended adjustment, thus dispensing with the usual locking devices.

The slot 33 in the arm 32 is of the length to provide the usual limitation found most convenient in devices of this general character to the double elongation of the form; that is, to the extension of the foot and heel parts in simultaneous opposite directions of movement, the front part forwardly and the heel part rearwardly. The structural principles of my invention, however, enable an additional extension of the foot part of the form separate from and independently of the heel part, the purpose of which, as hereinbefore stated, is to enable the use of the form for much larger sized shoes than has heretofore been possible in a form of this type adapted to the smaller or normal sizes of shoes. In other words, in my novel shoe form, one such form may be used for practically all sizes of shoes instead of the form being restricted to certain rather narrow ranges of sizes and thus requiring different forms for the different ranges of sizes of shoes.

In the present illustrative embodiment of the invention, with its operating mechanism as shown, the above-referred to object is attained by considerably extending the length of the screw shaft 13 within the foot part 10 beyond the operating length of the screw shaft 14 and beyond the operating length of either screw shaft under the limitations here-

inbefore referred to as imposed upon the double-elongation operation. By this arrangement, when the form is to be used in a shoe of extremely large size, the first extension made is that of the foot part, this extension being made prior to the insertion of the form in the shoe and simply by rotating the foot part upon its associated screw shaft in a direction to advance that part forwardly sufficiently to accommodate for the larger size of shoe beyond the accommodation afforded by the normal double-extension operation. Then, with the heel part not yet extended, the form is inserted in the shoe, that insertion being readily done because of the larger shoe opening, and the handle 28 is turned in the direction required to produce the usual double extension, that is the simultaneous forward and rearward movements of the foot and heel parts, respectively. To retract the form for its removal from the shoe, the handle 28 is turned in the opposite direction.

In the foregoing connection, it is to be noted that the screw shafts 13 and 14 are threaded in the same direction of threading, and that the simultaneous opposite directions of movement of the foot and heel parts are due to the fact that the two screw shafts are rotated in opposite directions by the oppositely disposed bevel gears 21 and 22, which in turn receive their own opposite directions of rotation from the single co-acting bevel gear 29.

What is claimed is:

1. An extensible shoe form comprising, in combination, separate fore and heel parts and screw means selectively operable to extend or retract said form by imparting simultaneous separating or approaching movements to both said parts while the form is in position in the shoe, and means having a manually operable part for operating said screw means, the manually operable part in all its operating positions being wholly above said fore and heel parts when the form is in the shoe, said screw means including means enabling said fore part to be independently extended from or retracted toward said heel part.

2. An extensible shoe form comprising, in combination, separate fore and heel parts, a screw shaft in threaded relation with said fore part and an aligned screw shaft in threaded relation with said heel part, gears on the adjacent opposed ends of said shafts and a gear in coacting engagement with said gears on said shaft for operating the same, said gears and shafts cooperating to form a rigidly locked connection between said fore and heel parts for all extension adjustments thereof.

3. An extensible shoe form comprising, in combination, separate fore and heel parts, a screw shaft in threaded relation with said fore part and extending therefrom toward

said heel part, a sleeve on said heel part extending toward said fore part and a screw shaft in threaded relation with said sleeve and extending therefrom toward and in alignment with said first mentioned screw shaft, gears on the adjacent opposed ends of said shafts, a gear coacting with said gears on said shafts, and means for rotating said coacting gear.

4. An extensible shoe form comprising, in combination, separate fore and heel parts, rotatable shaft means having threaded screw connections with said fore and heel parts for adjustably extending and retracting said form, and gears mounted wholly between and independently of said fore and heel parts to operate said shaft means, said screw connections having a steep pitch relative to the pitch of said gears whereby fine adjusting movements of said fore and heel parts may be imparted by operation of said gears and whereby said shaft means and said gears form a rigid abutment between said fore and heel parts holding them to their adjusted position when the form is under pressure in the shoe.

5. An extensible shoe form comprising, in combination, separate fore and heel parts, rotatable screw-shaft means extending in screw-threaded relation with said fore and heel parts whereby when the form is in the shoe rotation of said screw-shaft means in opposite directions effects separating and approaching movement to said parts in simultaneous opposite directions of positive movements of both of said parts along said screw-shaft means, manually-operable means for said rotation of said screw-shaft means while the form is in the shoe, said screw-shaft means having a greater extension of screw-threaded relation with one of said parts of said form than with the other and said one part being freely mounted on said screw-shaft means whereby before the form is placed in the shoe said one part may be turned on said screw-shaft means to increase the extension range of said form.

6. An extensible shoe form comprising, in combination, separate fore and heel parts, rotatable shaft means having screw connections with said fore and heel parts for adjustably extending and retracting said form, two gears mounted on said shaft means to rotate the same, another gear coacting with both said first-mentioned gears to turn the same, and means for manually turning said other gear, said screw connections having threads of steep pitch relative to said gears, whereby said shaft means and said gears form a rigid abutment between said fore and heel parts holding them to their adjusted positions when the form is under pressure in the shoe.

In testimony whereof I hereunto affix my signature.

WILLIAM BOUDINOT CONNER.
